UNITED STATES PATENT OFFICE.

AMOS B. WHEELER, OF MANCHESTER, CONNECTICUT.

WINDOW-FIXTURE.

SPECIFICATION forming part of Letters Patent No. 785,138, dated March 21, 1905.

Application filed August 2, 1904. Serial No. 219,162.

To all whom it may concern:

Be it known that I, AMOS B. WHEELER, a citizen of the United States, residing at Manchester, in the county of Hartford and State of Connecticut, have invented a new and useful Window-Fixture, of which the following is a specification.

This invention relates to a fixture which is designed to be attached to a window-casing for holding a curtain-pole, a curtain-rod, a light window-shade, and a dark window-shade.

The object of the invention is to provide a very simple and cheap fixture for this purpose which can be readily attached either to the front face or side face of a window-casing.

The embodiment of the invention that is illustrated consists of a light fixture which has an ear with holes whereby it may be fastened by screws to the front face of a window-casing, an offset with holes whereby it may be fastened by screws to the side face of a window-casing, an arm curved to receive a curtain-pole, fingers extending from the arm for holding a curtain-rod, and a leg with an opening for receiving the spindle of a shade-roller, and an opening that is lower than and is in front of the other opening for receiving the spindle of another shade-roller.

Figure 1 of the views is a plan illustrating a pair of the fixtures attached to the front faces of a window-casing. Fig. 2 is a plan illustrating a pair of the fixtures attached to the side faces of a window-casing. Fig. 3 is a side elevation of one fixture, and Fig. 4 is a side elevation of the other fixture.

It is preferred to stamp these fixtures out of sheet metal, such as brass, so that they will be light; but they may be cast to shape, if desired.

Each fixture has at the inner end an ear 2, which stands at right angles to the main portion of the fixture and is provided with perforations for the passage of the screws 3, which are used for fastening it to the front face of a window-casing. Extending outwardly from the ear of each fixture is an offset section 4, which is provided with perforations for the passage of screws 5, which are used to fasten the fixture to the side face of a window-casing. The ear which is used for

fastening the fixture to the front face of a window-casing and the offset which is used for fastening the fixture to the side face of a window-casing form the base of the fixture.

The body 6 of the fixture extends forwardly from the base, so that it will be inset when the fixture is attached to the side face of a window-casing. The arm 7 curves forwardly from the upper part of the body in such manner that it will receive and hold an end of a curtain-pole. At the outer end of this arm are a pair of upwardly-extending fingers 8, between which an end of a curtain-rod may be placed. The leg 9 extends downwardly and forwardly from the lower part of the body. In the leg of one fixture is an angular mortise 10 for receiving the angular end of the spring-spindle of a shade-roller, and farther down and a little in front in the same leg is an angular mortise 11 for receiving the angular end of the spring-spindle of another shade-roller. The other fixture has a similar curtain-pole arm and curtain-rod fingers; but instead of having angular mortises for the angular ends of the spring-spindles of shade-rollers has round perforations 12 for receiving the round ends of the fixed spindles of shade-rollers.

The mortises and perforations for the shade-rollers are in different horizontal planes, and they are also in different vertical planes, so that a dark shade may be held by the upper mortise and perforation and a light shade may be held by the lower mortise and perforation, at the same time allowing the dark shade to be drawn down behind the light shade. By reason of the offset sections these fixtures may be attached to the side faces in such manner that the ends of a pole or rod or the ends of shade-roller spindles will be properly supported without coming in contact with the face of the window-casing. These fixtures may be formed to shape in a cheap manner and they may be finished in any desired style.

The invention claimed is—

A window-fixture having a body, a section offset from the body, perforations through the offset section for the passage of holding-screws, an ear extending at right angles to the offset section, perforations through the

ear for the passage of holding-screws, an arm curving forwardly from the body, so as to form a pole-recess, fingers extending upwardly from the end of the arm so as to form 5 a rod-recess, and a leg extending downwardly from the body and having two openings adapted to receive the ends of shade-roller spindles,

one opening being lower than and farther forward than the other opening, substantially as specified.

AMOS B. WHEELER.
